UNITED STATES PATENT OFFICE.

ANGELO ROBERT CLAS, OF SHEBOYGAN FALLS, WISCONSIN, ASSIGNOR TO FALLS MACHINE COMPANY, OF SHEBOYGAN FALLS, WISCONSIN, A CORPORATION OF WISCONSIN.

GLUE-JOINTER ADJUSTMENT.

1,230,379.

Specification of Letters Patent. Patented June 19, 1917.

Application filed June 26, 1916. Serial No. 105,819.

To all whom it may concern:

Be it known that I, ANGELO ROBERT CLAS, a citizen of the United States, and resident of Sheboygan Falls, in the county of Sheboygan and State of Wisconsin, have invented new and useful Improvements in Glue-Jointer Adjustments, of which the following is a description, reference being had to the accompanying drawings, which

10 are a part of this specification.

This invention has for its object to provide a continuous feed glue jointer with side bars capable of independent adjustment at either end thereof but also adapted for simultaneous adjustment at both ends of both side bars by a single adjusting means.

Heretofore the side bars of continuous feed glue jointers have had adjusting screws at each end thereof and a change of adjustment of the machine, as when changing from work of one thickness to work of a different thickness required the changing of the four adjusting screws to the same extent.

25 An object of the present invention is to embody a single adjusting means in the bed of the machine for simultaneously operating all four adjusting screws, thus assuring equal adjustment throughout with a saving in time required for the adjustment.

With the above and other objects in view the invention consists in the glue jointer adjustment as herein claimed and all equivalents.

35 Referring to the accompanying drawings, in which like characters of reference indicate the same parts in the different views:

Figure 1 is a plan view of a glue jointer adjustment constructed in accordance with 40 this invention, the outline of the continuous feed glue jointer being shown in dotted lines;

Fig. 2 is a side view thereof;

Fig. 3 is an end view thereof;

45 Fig. 4 is an end view on an enlarged scale with parts broken away;

Fig. 5 is a plan view on an enlarged scale with the side bar lugs sectioned; and,

Fig. 6 is a detail view of one of the helical gear yokes.

In these drawings 9 indicates the bed or frame of a continuous feed glue jointer on which is mounted the central endless feed chain 10 as usual. The upper edges of the

55 bed form parallel work supports 11 on which

strips of lumber are passed through the machine standing on edge. The work is held firmly against the traveling feed chain by means of side bars 12 carrying a number of spring pressed bearing rollers 13 bearing 60 with pressure against the work as usual.

Instead of individually operated adjusting screws for moving the ends of the side bars 12 toward or away from the central feed chain a multiple screw feed is provided for 65 this purpose. Cross shafts 14 are journaled in bearings in the sides of the frame 9 with their ends projecting beyond the latter and having screw sleeves 15 held thereon by means of removable screw pins 16 passing 70 diametrically through them. Side bar supporting brackets 17 form housings inclosing these projecting ends of the cross shafts, and the side bars 12 at each end slide thereon and have downwardly projecting lugs 18 75 through which the screw sleeves 15 are threaded. Fixed at the center of each cross shaft 14 is a helical gear 19 confined between yoke arms of a bearing bracket 20. The bracket 20 has an inclined foot portion 80 bearing on an inclined portion of the frame and secured thereto by means of studs 21 threaded into the frame, and on either side of these studs are set screws 22 with lock nuts permitting of the vertical adjustment 85 as well as angular adjustment transversely and longitudinally of the frame in order that the bearings of the bracket may be properly aligned. A longitudinal shaft 23 is journaled at its ends in the brackets 20 and has helical gears 24 fixed thereon and confined between yoke arms of the brackets and meshing with the helical gears 19.

One end of one of the cross shafts 14 extends through the end of the side bar supporting bracket 17 and has a hand wheel or crank handle 25 thereon by which it may be turned.

In operation the turning of the cross shaft 14 by means of the hand wheel 25 not 100 only sets in motion the screw sleeves 15 thereon, but also through the longitudinal shaft 23 and the helical gear connections causes the other cross shaft 14 to turn and impart movement to the other two screw 105 sleeves. The direction of the threads of the screw sleeves as well as the direction of the oblique teeth of the helical gears causes all four screw sleeves to produce a like effect, the turning of the hand wheel in one direc- 110

- tion serving to move both ends of both side bars inwardly toward the feed chains, while the turning of the hand wheel in the opposite direction produces the opposite result.
- 5 Should independent adjustment be desired it may be accomplished by removing one of the screw pins 16 so as to free the screw sleeve from the cross shaft 14, and then by turning the screw sleeve independently, 10 as by means of a spanner wrench, the adjustment may be made and the screw pin returned. Thus one of the side bars may have one end set nearer to or farther from the feed chain without affecting the others.
- 15 What I claim as new and desire to secure by Letters Patent is:
1. In a glue jointer, a central feeding means, side bars on opposite sides thereof, and a screw adjusting means having threaded engagement with both ends of both side bars for moving them simultaneously toward or away from the feeding means, said side bars forming with the feeding means work clamping guides of equal widths in the various adjustments.
  2. In a glue jointer, a central endless feed chain, a side bar on either side thereof containing spring pressed rollers for holding work against the feed chain, and an adjusting means having threaded engagement with both ends of both side bars for moving them simultaneously toward or away from the feed chain to form equally variable work feeding clamping guides between them.
  3. In a glue jointer, a central feeding means, side bars on opposite sides thereof having bearing means for engaging work and holding it against the feeding means, cross shafts having threaded engagement 40 with the ends of the two side bars, a longitudinal shaft having helical gear connections with the cross shafts, and means for turning one of the shafts for producing simultaneous adjustment of the side bars 45 toward or away from the feeding means to form equally varying work clamping feed guides between them.
  4. In a glue jointer, a central feeding means, side bars on opposite sides thereof having bearing means for engaging work and holding it against the feeding means, cross shafts, screw sleeves on the cross shafts detachably connected therewith and threaded in the side bars, a longitudinal shaft having helical gear connections with the cross shafts, and means for turning one of the shafts for producing simultaneous adjustment of the side bars toward or away from the feeding means for equally varying the 60 width of the work feeding clamping guides between the side bars and the feeding means.
  5. In a glue jointer, a frame, a central feeding means thereon, side bars on opposite sides of the feeding means having bearing means for engaging work and holding it
- against the feeding means, cross shafts journaled in the frame and having threaded engagement with the ends of the side bars, yoke brackets adjustably mounted on the frame and having yoked bearings for the 70 cross shafts, a longitudinal shaft journaled in the brackets, helical gears on the cross shafts and on the longitudinal shaft meshing with each other and confined between yokes of the brackets, and means for turning 75 one of the shafts for producing simultaneous adjustment of both ends of both side bars.
6. In a glue jointer, a frame, a central endless feed chain thereon, cross shafts journaled in the frame with their ends projecting beyond the sides of the frame, supporting brackets secured to the sides of the frame and forming housings inclosing the projecting ends of the cross shafts, side bars 80 slidably mounted on the supporting brackets and having bearing means for engaging work and holding it against the feed chain, screw sleeves fitting on the projecting ends of the cross shafts, screw pins removably 85 securing the screw sleeves to the cross shafts, lugs on the side bars passing through openings of the supporting brackets and threaded on the screw sleeves, yoke brackets adjustably secured to the frame and having yoke arms in which the cross shafts are mounted, helical gears on the cross shafts between the yoke arms, a longitudinal shaft journaled in the yoke brackets, helical gears 90 thereon meshing with the first mentioned 95 helical gears and confined between yoke arms of the yoke brackets, and a crank handle secured to one of the cross shafts.
7. In a glue jointer, a central feeding means, side bars on opposite sides of the 105 feeding means forming work clamping and feeding guides therewith, a screw adjusting means for threaded engagement with both ends of both side bars for moving them simultaneously toward or away from the 110 feeding means for equally varying the widths of the two work feeding guides, said screw adjusting means being also capable of independent adjustment for either end of either side bar.
8. In a glue jointer, a central feeding means, side bars on opposite sides thereof, and a screw adjusting means having threaded engagement with both ends of both side bars for moving them simultaneously toward 120 or away from the feeding means to equally vary the widths of the two work feeding clamping guides formed between the side bars and the feeding means, such threaded engagement of the screw adjusting means 125 with the ends of the side bars comprising screw sleeves loosely mounted on shafts with means for connecting them with the shafts whereby independent adjustment of either end of the side bars may be made.

9. In a glue jointer, a central feeding means, side bars on opposite sides of the feeding means forming work clamping and feeding guides between them, a pair of cross shafts geared together, screw sleeves on the cross shafts threaded in the ends of the side bars, means for turning one of the shafts for producing simultaneous adjustment of the side bars toward or away from the feeding means to vary the widths of the work

feeding and clamping guides, and means for disconnecting the screw sleeves from the cross shafts for independent adjustment of either end of either side bar.

In testimony whereof I affix my signature, 15
in presence of two witnesses.

ANGELO ROBERT CLAS.
